(57) **CLAIM**

The ornamental design for a broadband dual-polarization horn antenna, as shown and described.

DESCRIPTION

FIG. 1 is a perspective view of a broadband dual-polarization horn antenna design showing my new design.

FIG. 2 is a front view of a broadband dual-polarization horn antenna.

FIG. 3 is a rear view of a broadband dual-polarization horn antenna.

FIG. 4 is a right side view of a broadband dual-polarization horn antenna.

FIG. 5 is a left side view of a broadband dual-polarization horn antenna.

FIG. 6 is a top view of a broadband dual-polarization horn antenna; and,

FIG. 7 is a bottom view of a broadband dual-polarization horn antenna.

Any shading and cross-hatching are not features of the design but are utilized to illustrate the surface contours of the broadband dual-polarization horn antenna design in the drawings.

The broken lines depict portions of the broadband dual-polarization horn antenna that form no part of the claimed design.

1 Claim, 7 Drawing Sheets
